UNITED STATES PATENT OFFICE.

MICHAEL WILFSON, OF BALTIMORE, MARYLAND, ASSIGNOR OF ONE-HALF TO MORRIS WILFSON, OF BALTIMORE, MARYLAND.

DESIGN FOR A MATCH-RECEPTACLE.

No. 39,907.

Specification for Design.

Patented April 6, 1909.

Application filed February 2, 1909. Serial No. 475,714. Term of Patent 7 years.

To all whom it may concern:

Be it known that I, MICHAEL WILFSON, a citizen of the United States, residing at Baltimore, in the State of Maryland, have invented a new, original, and ornamental Design for a Match-Receptacle, of which the following is a specification, reference being had to the accompanying drawing, forming a part thereof.

The figure is a perspective view of a match receptacle showing my new design.

I claim:

The ornamental design for match receptacle, as shown.

MICHAEL WILFSON.
